UNITED STATES PATENT OFFICE.

PAUL T. PLATT, OF NORFOLK DOWNS, MASSACHUSETTS.

RADIO WAVE METER.

Application filed April 6, 1925. Serial No. 21,005.

To all whom it may concern:

Be it known that I, PAUL T. PLATT, a citizen of the United States, and resident of Norfolk Downs, county of Norfolk, State 5 of Massachusetts, have invented an Improvement in Radio Wave Meters, of which the following description, in connection with the accompanying drawing, is a specification, like characters on the drawing representing like parts.

This invention relates to a radio wavemeter which is intended to be used for the purpose of assisting an operator to tune his receiving set to any predetermined wave 15 length, and for use especially in connection with the reception of radiotelephone broadcasting stations.

The invention provides a novel radio wavemeter which is relatively simple in construction, but which is highly efficient in operation and by means of which it is possible to tune a non-oscillating receiving set with very great accuracy to any desired wave 20 length within the range of the wavemeter.

The main object of the invention is to provide a radio wavemeter employing a single three-electrode vacuum tube which in operation is entirely silent of itself, but which oscillates at audio frequency, and 25 causes to be radiated a radio frequency wave modulated by an audio frequency wave that can be picked up on a non-oscillating receiver, and which produces a tone which is pure in character and which is very easy to 30 tune in sharply.

A device embodying my invention comprises an oscillating three-electrode vacuum tube, means to tune the associated circuit to any desired wave length within the range 35 of the instrument, said circuit being of such a design that a radio frequency wave is produced and radiated. Audio frequency oscillations are produced by reason of the fact that the circuit action causes the grid 40 of the vacuum tube to choke periodically, this blocking action causing periodic interruptions in the radio frequency oscillations which are inaudible in themselves, dividing them into groups of oscillations occurring 45 at much lower and audible frequencies, and thereby causing a radio frequency signal of low power modulated by an audio frequency 50 to be radiated, which signal can be picked up on a non-oscillating receiving set.

In order to give an understanding of the 55 invention I have illustrated herein a wiring

diagram for one embodiment thereof after which the novel features will be pointed out in the appended claim.

Fig. 1 is a wiring diagram illustrating the 60 principle of the invention;

Fig. 2 shows a part of a calibration sheet.

In the drawings 1, 2 and 3 indicates the filament, grid and plate respectively of a three-electrode vacuum tube. The filament 65 is connected to the low voltage or "A" battery 4 through a filament circuit 5, the latter having the usual rheostat 7 therein.

The high voltage or "B" battery is indicated at 8, this being connected to the plate 70 through the plate circuit 9 as usual.

10 indicates the grid circuit.

The main feature of the invention relates to the oscillation of a single tube at audio frequency in a wavemeter circuit, causing an 75 audio frequency signal to be radiated which can be picked up on a non-oscillating receiving set as a pure smooth note, sharply tuned to a predetermined wave length.

The theory of operation is as follows. A 80 large, double, plate winding specially interconnected, is close-coupled in fixed relation to the tuned grid inductance, and with filament circuit closed and a moderately high "B" battery potential applied to the plate, 85 there is a tendency to violent radio frequency oscillation. However, the grid condenser is bridged by a very high resistance grid leak, of such high resistance that the grid of the vacuum tube chokes periodically, 90 thus dividing the high frequency pulsations generated, into groups which occur at audio frequency, resulting in an audio frequency signal being radiated, which is tuned to the desired wave length by the variable con- 95 denser shunting the grid inductance.

The frequency of the audio wave may be varied within moderate limits by adjustment of the filament rheostat, such audio frequency variation having no effect on the 100 wave length calibrations. On a given rheostat setting there will be but very little variation in audio frequency at the opposite ends of the wave length scale of the wavemeter, this being due to the constants and arrangement of the grid and plate circuits, which are such that audio pulsations are freely produced throughout the wave length range of the instrument.

The frequency of the received audible 110 note corresponds to the frequency of the grid blocking action in the wavemeter, which

action changes an inaudible oscillation of say 1,000,000 cycles to an audible one of approximately 100 cycles, or higher as desired.

In the drawings the large double plate winding is shown at 11 and the tuned grid inductance with which this plate winding is close coupled is indicated at 12, 13 indicating the variable condenser by which the tuning is effected, said condenser being operated by any usual control.

21 indicates the usual grid condenser in the grid circuit and 14 is the high resistance grid leak which bridges said condenser.

One use for which this wavemeter is intended is to assist a person in tuning his receiving set exactly to any predetermined wave length.

In order to use the wavemeter it is necessary to have it calibrated and to employ a calibration curve or list. The calibration of the instrument consists in determining the wave length values corresponding to the various settings of the variable condenser, and which information must be obtained from a standard source before the wavemeter can be used as such.

I have shown in Fig. 2 a partial list of hypothetical calibration adjustments, the figures under the column labeled "Dial" indicating the reading by dial divisions for the variable condenser, and the figures in the column labeled "Meters" indicating the corresponding wave length. According to this calibration, if the variable condenser is set at 37 the vacuum tube produces radio frequency oscillations tuned to 300 meters wave length; if the variable condenser is set at 38, the wave length of the emitted signal will be 306 meters; a setting of the variable condenser at 39 will cause an audio radiation tuned to 312 meters, etc.

Assuming that the operator desires to set his receiving set for the reception of a broadcast on a 306 meter wave length, he will then adjust the variable condenser of the wavemeter to indicate "38" and when the filament circuit is closed through the rheostat the vacuum tube of the wavemeter will cause radio oscillations to be radiated tuned to 306 meter wave length.

The grid-choking action of the tube produces a radio frequency wave tuned to 306 meters which is modulated by audio frequency and may be readily picked up by the non-oscillating receiver and which comes in as a pure smooth tone.

In using the device the wavemeter may conveniently be placed from 1 to 10 feet

distant from the receiving set, according to the sensitivity of the receiver in question, and after the wavemeter has been adjusted for any particular wave length and set in operation the operator will tune his receiving set to the wavemeter, this being done by adjusting the controls of the receiving set until the wavemeter signal comes in clear and strong, and at maximum intensity. This can be readily done because of the smooth strong character of the audio frequency note.

The operator then knows that his set is turned exactly for the reception of radio transmission on a wave length of 306 meters. The wavemeter is then shut off and the receiving set is in condition to receive any broadcast which may be coming in on the 306 meter wave length.

The wavemeter may also be used for ascertaining the wave length of any broadcast which has been picked up by the receiving set. The wavemeter will be put in operation and its variable condenser rotated until the audio frequency wave generated by the wavemeter is distinctly heard together with the broadcast, after which a reading is taken of the wavemeter's condenser setting. This method will give accuracy to within a meter or two, and if greater accuracy is desired, the filament rheostat of the wavemeter may be adjusted so that straight radio frequency oscillations are produced, after which a zero beat adjustment on the broadcast station's carrier wave can be made, and from this more accurate information, the exact wave length determined.

I claim:

A radio wavemeter, said wavemeter comprising a single oscillating vacuum tube with filament, grid and plate circuits therefor, a two-section winding in the plate circuit, said sections being connected at their outer ends, a tuned inductance in the grid circuit situated between the inner ends of the two sections of the winding in the plate circuit, a grid condenser in the grid circuit and a high resistance grid leak bridging said grid condenser, whereby a periodic grid-choking action is produced which causes the radio-frequency oscillations to be broken into groups occurring at audio frequency over a wave length band of at least 188 to 555 meters.

In testimony whereof, I have signed my name to this specification.

PAUL T. PLATT.
